UNITED STATES PATENT OFFICE.

JAMES J. HARPUR, OF PITTSBURGH, PENNSYLVANIA.

DESIGN FOR A PEN-HOLDING ATTACHMENT FOR INK-BOTTLES.

56,064.

Specification for Design.

Patented Aug. 10, 1920.

Application filed December 5, 1919. Serial No. 342,853. Term of patent 7 years.

To all whom it may concern:

Be it known that I, JAMES J. HARPUR, a subject of the King of England, and a resident of Pittsburgh, Shadyside, in the county of Allegheny and State of Pennsylvania, United States of America, have invented a new, original, and ornamental Design for a Pen-Holding Attachment for Ink-Bottles, of which the following is a specification, reference being had to the accompanying drawing, forming part thereof.

Figure 1 is a top plan view; and Fig. 2 is a view in side elevation of a pen holding attachment for ink bottles illustrating my new design.

I claim:

The ornamental design for a pen holding attachment for ink bottles as shown.

JAMES J. HARPUR.
